UNITED STATES PATENT OFFICE.

PERRY JASPER JESSIP AND STEPHEN ADRIAN NOONER, OF ATCHISON, KANSAS.

AUTOMATIC SAFETY BUMPER.

Application filed January 11, 1924. Serial No. 685,556.

To all whom it may concern:

Be it known that we, PERRY JASPER JESSIP and STEPHEN ADRIAN NOONER, citizens of the United States, residing at Atchison, in the county of Atchison and State of Kansas, have invented certain new and useful Improvements in Automatic Safety Bumpers, of which the following is a specification.

The present invention relates to an automatic safety bumper for use upon rails to engage the trucks of a car or cars comprising a plurality of sections adapted to rigidly engage the rail.

A further object of the present invention is to provide a bumper arcuated to conform to the curvature of a car wheel and means for securing the sections rigidly together without bolting through the rail.

A still further conception of the invention will be had as the detailed description proceeds and referring more in detail to the drawing, wherein like reference characters indicate like or corresponding parts throughout the several views.

Figure 1 is a side elevation of the present invention,

Figure 2 is an end elevation showing the arc construction,

Figure 3 is an end elevation looking at the opposite side,

Figure 4 is an enlarged detailed side elevation of the intermediate section C, and

Figure 5 is a plan view looking down on the bumper.

Referring more in detail to the drawing, the bumper comprises side plates A and B and an intermediate plate C. The side plates A and B are provided with downwardly extending portions 1 at the base of the same adapted to fit tightly against the web of the rail X and engage the contour of the intermediate plate C. The side plates A and B are embraced through the short ribs 2 and are cut at an angle as shown at 3 so as not to interfere with the spikes which hold the rail to the tie rod. The side plates A and B are provided with an offset portion 4 cut back to the approximate width of the rail X.

Spaces 5 are provided between side plate A and intermediate plate C and side plate B and plate C to allow for the reaction of the bumper when engaged suddenly with the wheel of a car truck, while a space 6 is provided between the intermediate plate C and the rail X to allow for a gripping

action upon the rail when operated. The intermediate plate C is arcuated as at 7 to approximately the radius of a standard car wheel. This arc is constructed the width 60 of the rail and cast or otherwise formed onto the edge of the plate C is a flange 8 cooperating with the arcuated portion 7. At the bottom of the intermediate plate C there are provided notches or biting teeth 9 adapted 65 to engage the rail X when pressure is brought upon the plate C. For the purpose of resiliency the plate C is provided with cut out portions 10 and 11.

Holes 13 are formed in the side plates A 70 and B and slotted or elongated holes 14 are formed in the intermediate plate C in parallel alignment with the holes 13 in plates A and B. By this construction the side plates A and B and intermediate plate C 75 can be clamped over the rail without bolting through the rail and allow the plate C to grip the rail X when pressure is applied by the car wheel. Bolts 15 rigidly secure the side plates A and B and plate C 80 in assembled relation.

The base 12 of the plate C is not as wide as the rail ball. This is done in order that the plates A, B and C fit tightly over the rail and as soon as pressure is applied on 85 the plate C, and the arc 7 and flange 8, it will draw the weight on the notches or teeth 9. When the weight is applied on the notches 9 it will have a tendency to raise the bottom 1 over the plates A and B against 90 the bottom of the rail which will make a complete automatic grip and not permit the bumper to slide on the rail.

The inner face of plates A and B and bottom sides of C are practically smooth 95 and flat and in practice the plates A, B and C are clamped over the rail with another set of plates of the same construction directly opposite on the other rail, making a complete automatic bumper on each rail for 100 the trucks of the car or cars. The bumpers when installed as described provide a most efficient obstruction impending further progress or travel of the car or cars. The arc-shaped ends and faces of the bumpers extending 105 or lying in the vertical plane of the rail and the bumpers being of a height to receive the impact or shock from the lower rail quadrants of the wheels prevent or hold the car or cars from running over 110 the bumpers.

Our automatic rail clamps may be manu-

factured at and produced at a low cost and as will be evident, may be readily and conveniently installed at very little expense. It will also be noticed it will not be necessary to drill any holes in the rail and a few bolts are all that are required to install or erect a set of our bumpers.

What is claimed is:

1. A chock block comprising side plates, an intermediate plate provided with notches, means for rigidly securing said plates over the rail causing said intermediate plate to grip the top rail and prevent disengagement of said side plates.
2. A car bumper including plates adapted to seat upon the rail, integral extensions protruding downwardly adapted to engage part of the ball, wall and top of the rail

and a means for securing said plates to the rail without drilling through said rail.

3. A car bumper comprising separate sections substantially of plate formation, adapted to seat in upright flatwise abutting position upon and embrace the ball and web of the rail, each section being grooved at its base in conformity with one-half of the ball of the rail and having a base extension adapted for engagement with the web of the rail and means for bolting through the section above the rail for separately gripping the sections together.

In testimony whereof we affix our signatures.

PERRY JASPER JESSIP.
STEPHEN ADRIAN NOONER.
